DRINKING VESSEL

Thomas Edward Pickering and John Russell
Pickering, London, England

Application October 20, 1948, Serial No. 55,582

Claims priority, application Great Britain
March 24, 1948

8 Claims. (Cl. 65—13)

1

This invention concerns drinking vessels, and has for a primary object to provide a child's drinking vessel from which all the contents may be drained without the necessity for the child to bend its head back.

Hitherto, it has been customary for the rim of the mouth of a mug or beaker or like drinking vessel to lie in a plane normal to the axis of the mug, and concentric with the base thereof. This results in the part of the rim opposite the point at which a child drinks engaging the child's forehead and preventing the contents from being drained unless the child bends its head well back. Young children, especially babies, are not easily taught to do this without spilling much of the contents of the vessel, and the present invention aims at overcoming this difficulty in a simple and effective manner whilst enabling the general ratio, for a mug or beaker, between the diameter of the free surface of the liquid and the depth thereof to be retained. This provision ensures that the rate of heat loss for a warm or hot drink will be of the same order as for a normal type of mug or beaker.

According to the present invention, a drinking vessel has the mouth at its upper end offset laterally with respect to the bottom of the vessel, the lip or point of maximum projection of the rim of the mouth beyond the said bottom being connected thereto, as seen in vertical section, by a substantially rectilinear front wall part meeting the rim at an angle less than 90° and the centre of gravity of the vessel lying vertically above a point within the said bottom or within a base which includes the bottom and an extension thereof beyond the side walls of the vessel.

For the purposes of this specification, the bottom of the vessel is regarded as the area enclosed by the lower edge of the side wall or walls. The base, on the other hand, is defined as the full surface area which is operative to support the vessel, and may be co-extensive with or project beyond the bottom. Thus, for example, the base of the vessel may comprise the bottom thereof, together with a co-planar extension located externally of the walls of the vessel below the lip on the mouth.

Preferably the rim of the mouth lies in a plane substantially parallel to that containing the bottom of the vessel.

The vessel is conveniently of generally cylindrical form, and the substantially rectilinear front wall part connecting the bottom to the lip on the rim of the mouth may with advantage meet the plane of the said rim at an angle of approximately 60°.

2

Various alternative embodiments of the invention as applied to a baby's drinking mug will now be described, by way of example only, with reference to the accompanying drawings in which—

Fig. 1 is a side elevation of one form of drinking mug;

Fig. 2 is a plan view of the mug shown in Fig. 1;

Fig. 3 is a side elevation of a second form of mug;

Fig. 4 is an underplan view of the mug shown in Fig. 3;

Fig. 5 is a sectional plan view of another form of mug taken on a plane parallel to and adjacent the bottom of the mug;

Fig. 6 is a perspective side view of a further embodiment of the invention;

Fig. 7 is a plan view of the mug shown in Fig. 6;

Fig. 8 is a side elevation of a still further alternative form of mug having a modified handle arrangement.

Fig. 9 is a sectional elevation of an alternative construction of the form shown in Fig. 8;

Fig. 10 is a sectional elevation of yet another construction of mug;

Fig. 11 is a side view showing the form of mug illustrated in Figs. 1 and 2 when in use;

Fig. 12 is a plan view showing a modified shape of mug, and

Fig. 13 is a side elevation of a different shape of mug.

Throughout the drawings, like parts carry similar reference numerals.

Referring first to Figs. 1 and 2 of the drawings 35 the mug 1 is of substantially cylindrical shape having its axis 2 inclined to the vertical at an angle of the order of 30°. The rim 3 of the mouth at the upper end of the mug 1 is of elliptical shape (see Fig. 2) and lies in a plane parallel to the plane of the bottom 4 of the mug, and the point 5 on this rim 3 which projects furthest beyond the said bottom 4 constitutes the drinking lip, and is connected to the bottom by a forward-sloping rectilinear front wall part 6 as seen in vertical section through the major axis of the ellipse of the mouth. On the opposite side of the mug 1, the rear wall 7 has a short vertical part-cylindrical section 8 adjacent the bottom 4, this vertical section merging smoothly into the curvature of the inclined cylindrical outline of the mug 1 and constituting what may be termed a "heel" part of the mug. At a convenient position on one side of the mug is mounted a handle 9, although a drinking vessel according to the invention may have more than one

handle (see, for example, Fig. 7) or no handle (see Fig. 13) as desired.

The mug 1 is thus of generally cylindrical shape, inclined towards the drinking lip 5 when viewed from the side, and its walls are preferably of uniform thickness whilst its bottom 4 is thickened, as shown in Fig. 9.

The proportions of the mug are usually the same as those of a normal upright children's mug, and the angle of inclination of the axis 2 of the mug is not so great as to cause the centre of gravity (shown at G in Fig. 1) to lie in advance of the vertical through the point 10 on the bottom 4 below the lip 5 and opposite what has been termed the heel 8. It may be, however, that the centre of gravity G is, nevertheless, thought to be sufficiently close to this vertical that the stability of the mug 1 when in use is unduly lessened having regard to the possibility of jolting or shaking of the table or tray on which the mug is normally placed when full.

In order to improve the stability of the mug 1, the bottom 4 thereof may be extended beyond the point 10 to provide a base 12 which is of greater extent than the bottom 4 of the vessel 1 and off-set with respect thereto in the direction of the lip 5 on the mouth. This extension may be in the form of a relatively short crescent-shaped tongue 13 blending into the front wall 6, as shown in Fig. 3, or it may be in the form of a flat arcuate plate of "half-moon" shape. Alternatively again, as shown in Fig. 5, the base may be constituted by a circular or substantially circular disc 12a having a common tangent with the bottom 4 at the heel 8 thereof but off-set with respect thereto in the direction of the lip 5 on the mouth. Such a disc-like base 12a may be flat or may have an up-turned rim 12b (Figs. 6 and 7) to constitute in effect an integral eccentric saucer. The upturned rim 12b may blend into the wall of the mug 1 at the heel part 8 or it may be continuous all round the saucer as preferred. The base may be of polygonal or other shape as desired.

In a further modification, shown in Fig. 8, a handle 9a may be formed on or secured to the front wall part 6 of the mug 1 in a vertical plane at a point below the lip 5, the lower end of the handle 9a terminating at a point 9b in the plane of the base 4 of the mug to constitute a strut or steady therefor. The handle 9a may be curved, as shown, or it may be straight, as shown at 9a in Fig. 9, in which also its lower end is shown returned at 9c towards the bottom 4 of the mug and secured to the front wall part 6 thereof to form a closed loop.

In addition to the use of a base 12 or an extended bottom 13 of the mug 1, the lower end of the rear wall adjacent the heel 8, or the bottom 4, or both, may be thickened, as at 8a in Fig. 10, or otherwise increased in weight, as by a metal insert 14, so that this portion acts as a counter-weight to oppose tipping of the mug in the direction of the inclination of its axis 2.

In use, the child drinks from the lip 5 of the mug, the angle between the line of the front wall part 6 of the mug and the plane containing the rim 3 of the mouth at this point being of the order of 60°. Thus, when the child tips the mug 1, the inclined front wall part 6 passes through the horizontal position before the further side 5a of the rim 3 makes contact with the child's forehead 14 (see Fig. 11) and so enables all the contents of the mug to be drained without the necessity for the child to bend its

head back. Moreover, with a mug of normal capacity, the size of the free surface of the liquid is not substantially greater than is encountered in a mug of the same capacity and of usual upright design. Thus a warm drink will retain its heat for about the same period of time.

Other formations than cylindrical may be adopted as desired; for example, as shown in Fig. 12, the mug may be of hexagonal section in plan, having a short vertical wall portion 8 at the heel thereof. It may alternatively be of square or other polygonal shape in plan or horizontal cross-section. The short vertical wall section at the heel of the vessel may be omitted as indicated in Fig. 13, and the line of the rear wall 7 may be continued downwards to the bottom without a break. Any convenient material may be used in the manufacture of the mug.

What we claim is:

1. A drinking vessel constituted by a single hollow container which is generally parallel-sided when seen in cross-section on a plane containing the axis of the body, said axis being inclined forwardly with respect to a plane vertical to the base thereof, and an open mouth at the upper end of the vessel, the rim of which lies wholly in a plane parallel to the plane of said base, the center of gravity of said vessel lying on a line drawn through the base and normal to the plane thereof, and a portion of the side wall of the vessel adjacent the base opposite the point of greatest overhang of the side wall being formed substantially at right angles to said base.

2. In a drinking vessel, a single liquid container having a base and side walls, the upper ends of said side walls constituting the rim of the mouth of said container, said rim lying in a plane parallel to the plane of said base, the forward portion of said rim serving as a drinking portion, the axis of said container being inclined upwardly and forwardly with respect to said base, the walls of said container being substantially straight in vertical section and parallel to said axis over at least the upper parts of their lengths, and the center of gravity of said container lying vertically above a point in the base of said container when said base acts as a horizontal surface.

3. A drinking vessel comprising a single liquid container having its axis inclined forwardly with respect to the base of the vessel, said container having its upper end open to constitute the mouth of the vessel, the rim of the mouth lying in a plane substantially parallel to the plane of the base, opposite portions of the walls of said vessel being substantially straight and parallel to said axis over at least the upper parts of their lengths, and the center of gravity of said vessel lying vertically above a point in the base when the base rests on a horizontal surface.

4. A drinking vessel constituted by a single hollow container which is generally parallel-sided when seen in cross-section on a plane containing the axis of the body, said axis being inclined forwardly with respect to a plane vertical to the base thereof, and an open mouth at the upper end of the vessel, the rim of which lies wholly in a plane parallel to the plane of the said base, the center of gravity of said vessel lying on a line drawn through the base and normal to the plane thereof, a portion of the side wall of the vessel adjacent the base opposite the point of the greatest overhang of the side wall being formed substantially at right angles to the base and a handle attached to the wall at a point adjacent the point of maximum projection of the rim of the

mouth beyond the bottom and extending to a point lying in the plane containing the base of the vessel.

5. A drinking vessel as set forth in claim 3, wherein a portion of the side wall of the vessel adjacent the base opposite the point of greatest overhang of the side wall is formed substantially at right angles to said base.

6. A drinking vessel as set forth in claim 5, wherein the side wall portion which is formed at right angles to said base is thickened to form a stabilizing counterweight for said vessel.

7. A drinking vessel as set forth in claim 6, wherein the thickened portion of the wall adjacent the base of the vessel has embedded therein a mass of a material having a greater density than the material of the rest of said vessel.

8. A drinking vessel as set forth in claim 3, wherein a handle is attached to a wall adjacent the point of maximum projection of the rim of the mouth beyond the bottom of the vessel and extends to a point lying in the plane containing the base of said vessel.
